UNITED STATES PATENT AND TRADEMARK OFFICE
CERTIFICATE OF CORRECTION

PATENT NO. : Des. 528,552 S
APPLICATION NO. : 29/190933
DATED : September 19, 2006
INVENTOR(S) : Nevill-Manning et al.

Page 1 of 3

It is certified that error appears in the above-identified patent and that said Letters Patent is hereby corrected as shown below:

The title page showing the illustrative figure should be deleted to be replaced with the attached title page.

The drawing sheet, should be deleted to be replaced with drawing sheet, as shown on the attached page.

On the title page under item (57)

In the description, add before the first paragraph the following paragraph:

A portion of the disclosure of this patent document contains material to which a claim for copyright and trademark is made. The copyright and trademark owner has no objection to the reproduction of the patent document or the patent disclosure, as it appears in the U.S. Patent Office records, but reserves all other copyright and trademark rights whatsoever.

Signed and Sealed this
